Primary Examiner — Catherine Tuttle(74) Attorney, Agent, or Firm — James A. HudakCLAIM

I claim the ornamental design for a golf ball, as shown and described.

DESCRIPTION

FIG. 1 is a front elevational view of the golf ball showing my new design, that of a golf tee surface motif; and,

FIG. 2 is a rear elevational view thereof.

The broken line illustration of the golf ball is for illustrative purposes only and forms no part of the claimed invention.
